OIL BURNER

Walter J. Englert, Rochester, N. Y., assignor to
Peter J. Nagle, Rochester, N. Y.

Application July 26, 1932, Serial No. 624,766

8 Claims. (Cl. 158—87)

The invention relates to oil burners of the class designed for installation in domestic ranges, cooking stoves, and the like, and is preferably intended for burning a relatively heavy grade of fuel oil or one of a somewhat heavier grade than kerosene.

The invention has for its object to provide an improved burner of this type designed to vaporize the oil as fast as it is fed thereto, the resulting vapor being burned within suitable chambers or passages formed in the burner and communicating with a well which becomes sufficiently heated by the burning of an initial supply of the oil to insure vaporizing of the same within the well to which the oil is fed preferably by gravity.

A further object of the invention is to provide improved distributing means between the well and the chambers or passages in which the vapor is burned, whereby the latter is directed in separate streams to each of said chambers upon discharging from the well.

A further object of the invention is to provide an improved device arranged to overlie or project within the well, which becomes quickly heated and serves not only as a means for heating the oil within the well to vaporize the same, but also as means for positioning and securing one or more wicks within the well.

A further object of the invention is to provide an improved method of mounting and maintaining the wicks in proper position within the burner.

To these and other ends the invention resides in certain improvements and combinations of parts, all as will be hereinafter more fully described, the novel features being pointed out in the claims at the end of the specification.

In the drawings:

Fig. 1 is a plan view of a double burner with the chimneys to one of the burners removed;

Fig. 2 is a sectional elevation taken on line 2—2 of Fig. 1;

Fig. 3 is a detail section through a portion of the base of the burner, taken on the line 3—3 of Fig. 1;

Fig. 4 is a sectional elevation on line 4—4 of Fig. 1, and

Figs. 5 and 6 are detail elevations of the distributor plug which extends into the oil well as shown in Fig. 2.

The same reference numerals throughout the several views indicate the same parts.

In the present invention I have shown two burners connected one with another, and since the burners are similar in construction a description of one will be sufficient for both. Referring to the drawings 10 represents the base of the

burner which may be supported by suitable means, not shown. Extending upwardly from the base are four concentrically arranged walls 11, 12, 13, and 14, the walls 11 and 12 affording an outer oil vaporizing and vapor distributing groove or chamber 15 and the walls 13 and 14 forming an inner oil vaporizing and vapor distributing groove 16. Between the walls 12 and 13 is an annular space 17 for the upward passage of air entering the bottom of the burner through semi-circular openings 17a in the base thereof.

The upstanding walls are shouldered at 18 to afford seats for the lower ends of the four concentrically arranged stacks or chimneys 19, 20, 21, and 22 extending upwardly from the burner, as shown in Fig. 2. The walls of the chimneys are provided with perforations 23 for admitting air to the chambers through the sides thereof which assists in promoting and carrying off the products of combustion from the burner.

A removable cover 24 is provided for the chimneys 20, 21, 22, thus leaving the space between the chimneys 19 and 20 open for the free passage of the products of combustion from the vaporizing chamber 15. The cover plate is provided with openings 25 which register with the annular space between the chimneys 21 and 22 whereby the products of combustion from the vaporizing and vapor distributing chamber 16 are free to pass outwardly through the cover plate. Air entering the openings 17a in the bottom of the burner is choked by the overlying cover plate, and is thus caused to pass laterally through the perforations in the chimneys into the annular passages overlying the vaporizing grooves or chambers 15 and 16, thus mixing with the vapor in said passages and aiding and promoting combustion.

At one side of the base of the burner and depending therefrom is an oil well 26 having an inlet port 27 above the bottom thereof with which is connected a short pipe 28 arranged for connection with a suitable supply source, not shown. The bottom of the well is provided with a removable closure 29 to permit the well to be drained and cleaned from time to time. The mouth of the well, indicated by dotted lines at 30 in Fig. 1, lies between the spaced connecting portions 31 of the upstanding walls 12 and 13 of the burner. The mouth 30 is, therefore, so positioned that it communicates with both the inner and outer vapor distributing grooves 15 and 16.

Overlying and extending within the mouth of the well is a distributing plug 32 which is shown in section in Fig. 2. The plug has a shoulder 33 which rests on the base 10 of the burner,

whereby it is held in proper vertical position. The body of the plug comprises two pairs of upwardly extending ribs, one pair being indicated at 34, and the other at 35, the ribs depending from 5 the head 36 of the plug, which is held in spaced relation to the base 10 of the burner by the shoulder 33, as shown in Figs. 2 and 4. By constructing the plug in the manner described, it serves to divide the mouth of the oil well into four 10 separate passages, two at one side, and two at the opposite side, which discharge into the opposing ends of the outer and inner vaporizing and vapor distributing grooves 15 and 16 to insure even distribution of the vapor to said grooves in 15 or above which combustion takes place upon lighting the burner, as described hereinafter. The upper extremity 37 of the plug is in the plane of the lower ends of the burner chimneys, as indicated in Fig. 2, and forms a seat for portions 20 of the chimneys 20 and 21. The plug is prevented from turning in the well by the contacting of two sides of its head with the wall portions 31 which connect the vertical walls 12 and 13 of the burner.

25 Suitable wicks for the burner are provided, one indicated at 38 in the outer groove 15, and one at 39 in the inner groove 16. The inner wick 39 encircles the vertical wall 14 of the burner at the outer side thereof, and the outer wick 38 lies 30 against the inner face of the outer burner wall 11, as shown in Fig. 1. The ends of the wicks are coiled upon themselves, as indicated at 40, to an extent sufficient to fill the grooves within which they lie, said coils being preferably retained in 35 proper position through frictional engagement with the walls of the burner with which they contact. The coils 40 are placed diametrically opposite the distributing plug, the inner edge of the latter engaging and holding the wick 39 in 40 contact with the wall 14, and the outer edge of the plug engaging the wick 38 to hold it in contact with the outer wall 11 of the burner. The coils 40 of the wicks serve to close the grooves 15 and 16 at a point opposite the distributing plug so 45 that each groove is divided into two sections which insures a better and more even flow of the vapor within the grooves. The wicks are made of asbestos and readily become saturated with the oil which flows into and partially fills the grooves 50 when the burner is not in use, it being understood that at such time the oil will find its way from the well through the distributing passages of the plug, and that it will thus be discharged in opposite directions into the respective ends of 55 the grooves lying immediately opposite said passages.

It will be noted that the intermediate walls 12 and 13 of the burner are connected by radially extending ribs 41 which separate the air inlet openings 17a in the bottom of the burner.

60 Suitable connecting central and side walls 42 and 43 are provided between the burners, as shown in Fig. 1, the connections affording means for attaching the burner to a suitable support or supports, not shown.

The cover plate 24 for the chimney sections of 65 the burner is provided with a handle 44 by which it can be conveniently removed from the sections.

70 The wicks of the burner can be conveniently lighted by means of a suitable torch inserted downwardly within the passages formed by the walls of the chimneys, or in any other preferred manner.

75 In the operation of the burner the supply of

oil which has accumulated within the grooves 15 and 16 upon being ignited will be consumed in a comparatively short period, during which time the grooves 15 and 16 serve to some extent as vaporizing chambers, combustion of the oil vapor taking place at and above the tops of the wicks in the annular spaces between the chimneys. During this initial period of operation, the parts of the burner become heated, and the walls of the oil well and the distributing plug 10 therein will become sufficiently heated to bring the oil within the well to the boiling point. The oil is thus converted in the well 26 into vapor which escapes through the four passages of the 15 heated distributing plug into the grooves or chambers 15 and 16, which thenceforth serve mainly as vapor distributing channels, though if any fuel reaching these channels is incompletely vaporized, it may be completely or further 20 vaporized in these channels. The vapor rises from the channels into the spaces between the walls of the chimneys, mixes with air entering these spaces through the holes 23, and burns in 25 these spaces. Combustion continues until after the valve in the supply line, not shown, has been closed.

The distributing plug is also advantageous as a means for preventing the flames from entering the oil well during the burning of the vapor in 30 the chambers 15 and 16 and the overlying passages formed by the perforated walls of the chimney.

I claim:

1. A fuel oil burner comprising a base having 35 a plurality of vapor chambers, an oil vaporizing well communicating with said chambers and arranged to be heated by the burning of the vapor, means for supplying oil to said well, a distributor associated with the well and positioned to direct the vapor in separate streams to said chambers, and wicks within the chambers for burning an initial supply of oil accumulated within the chambers whereby to heat the well to effect vaporization of the oil therein, said distributor lying 40 against one side of one wick and serving to hold 45 said wick against one side of its chamber.

2. A fuel oil burner comprising a base having a plurality of concentrically arranged annular grooves formed by upstanding spaced walls and affording vapor receiving chambers, wicks encircling certain of said walls within the grooves, the wicks each having opposing ends, said ends being rolled each to a diameter corresponding substantially to the width of the grooves and resting therein to be held in position through frictional engagement with the walls of the grooves, a well carried by the base for vaporizing the oil, means for supplying oil to said well, and means for directing vapor from said well into 50 said grooves.

3. A fuel oil burner comprising a base having a plurality of concentrically arranged annular grooves formed by upstanding spaced walls and affording vapor receiving chambers, wicks encircling certain of said walls within the grooves, the wicks each having opposing ends, said ends being rolled each to a diameter corresponding substantially to the width of the grooves and resting therein to be held in position through frictional engagement with the walls of the grooves, a well carried by the base for vaporizing the oil, means for supplying oil to said well, and a distributor within the well having separate 55 passages leading to said grooves and adapted to direct vapor from said well into said grooves.

4. In a burner of the character described, a base having a plurality of fuel grooves therein, starting wicks located in said fuel grooves, a connecting groove extending only between and interconnecting said fuel grooves, means comprising a vaporizing chamber located in said connecting groove for supplying fuel to said fuel grooves, and a cover overlying said connecting groove and positioned to retain said starting wicks in position to permit the passage of vapors from said connecting groove into said fuel grooves. 5
5. A burner of the character described comprising a base having a plurality of spaced concentric fuel grooves and a covered connecting groove extending only between and interconnecting said fuel grooves, a vaporizing well located in the bottom of said connecting groove, an elongated member positioned vertically within said vaporizing well to conduct heat to fuel therein, 10 flutes lengthwise in said member providing a plurality of vertical vapor passages from said vaporizing well, and means supplying fuel to said vaporizing well. 15
6. A burner of the character described having a base comprising a plurality of spaced, concentric fuel grooves and a covered connecting groove extending only between and interconnecting said fuel grooves, a vaporizing well located in the bottom of said connecting groove, 20 a pipe connected to said vaporizing well for supplying fuel thereto, a ribbed member depending into said well to conduct heat to said fuel and to restrict the passage of vapors therefrom in said vaporizing chamber, and an extension on one of the ribs of said member to support said member on the bottom of said connecting groove. 25
7. A burner of the character described comprising a base having a plurality of spaced, concentric fuel grooves and a covered connecting groove extending only between and interconnecting said fuel grooves, a vaporizing well located in the bottom of said connecting groove, a fuel pipe connected to said vaporizing well for supplying fuel thereto, a member resting on the bottom of said connecting groove and depending partly into said vaporizing well to restrict the passage of vapors from said vaporizing chamber, flutes in said member providing vertical passages for said vapors, the cross-sectional area of said passages combined being less than the cross-sectional area of said vaporizing chamber. 30
8. A burner of the character described comprising a base having a plurality of spaced, concentric fuel grooves therein, a connecting groove extending radially across said base between said fuel grooves and interconnecting the same starting wicks in said fuel grooves, a cover plate overlying said connecting groove and extending partly over said fuel grooves and positioned between said starting wicks, a vaporizing well in the bottom of said connecting groove, and means for supplying fuel to said vaporizing well. 35

WALTER J. ENGLERT.
